UNITED STATES PATENT OFFICE.

NORMAN MACBETH, OF PHILADELPHIA, PENNSYLVANIA, ASSIGNOR TO WELSBACH LIGHT COMPANY, OF GLOUCESTER CITY, NEW JERSEY, A CORPORATION OF NEW JERSEY.

DESIGN FOR A CEILING-REFLECTOR.

41,377.

Specification for Design.

Patented May 16, 1911.

Application filed February 10, 1911. Serial No. 607,871. Term of patent 14 years.

To all whom it may concern:

Be it known that I, NORMAN MACBETH, a subject of the King of Great Britain, residing at Philadelphia, in the county of Philadelphia, State of Pennsylvania, have invented a new, original, and ornamental Design for Ceiling-Reflectors, of which the following is a specification, reference being had to the accompanying drawings, forming part thereof.

The figure is a perspective view showing my new design.

I claim:

The ornamental design for a ceiling reflector, as shown.

In testimony whereof, I have hereunto set my hand.

NORMAN MACBETH.
